Primary Examiner — Darcey E Gottschalk
Assistant Examiner — Vanessa M. Pursley(74) Attorney, Agent, or Firm — Design IP(57) CLAIM

The ornamental design for a beverage container, as shown and described.

DESCRIPTION

FIG. 1 is a perspective view of a beverage container showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a sectional view taken along line 8-8 of FIG. 6. In the drawings, the broken lines show portions of a beverage container that form no part of the claimed design.

1 Claim, 5 Drawing Sheets# US D978,617 S
